UNITED STATES PATENT OFFICE.

WARREN S. JOHNSON, OF MILWAUKEE, WISCONSIN.

THERMOSTATIC CIRCUIT-CLOSER.

SPECIFICATION forming part of Letters Patent No. 364,518, dated June 7, 1887.

Application filed July 30, 1886. Serial No. 209,561. (No model.)

To all whom it may concern:

Be it known that I, WARREN S. JOHNSON, of Milwaukee, in the county of Milwaukee and State of Wisconsin, have invented certain 5 Improvements in Electric Thermostats, of which the following is a specification.

My invention relates to that class of thermostats in which a compound expansion-bar is employed to open and close an electric circuit by coming in contact at its free end with one or more contact-points.

The aims of the invention are to simplify and cheapen the construction, to provide for accurate and instantaneous adjustments of the 15 instrument, so that it will close the circuit at one temperature or another, as demanded, and to prevent the accidental closing of the circuit.

Referring to the accompanying drawings, Figure 1 is a perspective view of my instrument. Fig. 2 is a similar view of the same looking from the rear. Fig. 3 is a vertical cross-section through the adjusting devices. Fig. 4 is a vertical section through the contact-points and stops.

25 In constructing my instrument I provide a bar or body, A, of wood or other suitable material which will remain unaffected by the ordinary changes of temperature. I prefer to employ a wooden frame or body and a thermometer, B, of ordinary material. To the upper and lower ends of the bar A, I secure metallic plates C and D, having their extremities curved backward and formed into ears 30 adapted for adjustment to a wall or other support. Thus formed these plates serve, in addition to the purposes hereinafter described, as supports or brackets to maintain the body A in position at a distance from the wall.

On the upper plate, C, is formed a stud or 40 pivot, a, which supports a lever, E, secured firmly to the upper end of the thermostat-bar F, so that the pivotal motion of the lever will have the effect of throwing the lower end of the bar F to the right or left. This bar may 45 be of any ordinary construction, such as is commonly employed in thermostatic instruments; but I prefer to construct the same of two strips of brass and hard rubber riveted or otherwise secured firmly together. By the 50 differential expansion of these two substances of which the bar is formed, under variations of

temperature the bar will be curved either to the right or left, as the case may be.

To the metallic portion of the bar F there is secured a conducting-finger, c, which is extended downward beyond the bar, as shown, between the two contact-points d and e, which latter are passed through and adjustably secured to the two insulated binding-posts f and g, mounted in the plate D, as shown. A third 55 binding-post, h, is also attached to the plate D and is in metallic contact therewith. The plate D is in turn in contact, as shown in Fig. 2, with a wire, i, or equivalent conductor attached to the plate C. The curvature of the 60 bar F consequent to the variations in temperature will throw its finger c into contact with one or the other of the points d and e, so that the current may pass from the binding-post h through the plate D, conductor i, plate C, 65 lever E, and bar F, and finger c to the binding-post f or g, as the case may be.

The lever E has one end extended downward and seated in the grooved end of a screw, G, which is in turn seated centrally within a 75 larger screw, H, mounted in a hub or projection, K, formed on the plate C. The larger screw H is commonly constructed with a thread of greater pitch than the other, and is provided with an operating arm or handle, I, which 80 sweeps over the face of a graduated plate, m, attached to the hub K, or otherwise supported. By turning the central screw, G, the lever may be moved and the thermostat-bar 85 adjusted in relation to the other parts in such manner as to effect the opening and closing of the circuit at the exact temperature required. Being thus adjusted, the screw G remains permanently in position unless some unusual circumstance shall render it necessary to readjust 90 the parts. By turning the handle I and the screw H the latter may be moved inward and outward, carrying with it the screw G, and thereby changing the position of the lever and of the bar in such manner that the circuit will 95 be opened or closed at a higher or a lower temperature, as occasion may demand.

Under ordinary circumstances the opposing contact-points are so adjusted that the conducting-finger has but a slight movement in passing from one to the other. In view of this fact it is necessary to provide stops to limit 100

the motion of the thermostat-bar, as otherwise an extreme movement of the bar would bend the conducting-finger in such manner that it would touch both contact-points at one time and thus form a short circuit.

I propose to employ stops of any suitable character; but in the present instance I have formed the lower plate or bracket, D, with two arms between which the thermostat passes and to by which its motion is restricted.

I commonly employ my thermostats in connection with valves for regulating the supply of steam to heating-coils and to valves for controlling the temperature of buildings, and it is in this connection that the mechanism shown is of peculiar advantage, since it enables the attendant to instantly adjust the device to maintain a higher or lower temperature, as may be required.

20 The employment of the thermometer-body as a means for supporting thermostatic devices is advantageous, in that the instrument is given a compact and ornamental appearance, and in that the thermometer is maintained at all times in position to serve as a guide for adjusting the thermostat and for determining the accuracy of its operation.

While I prefer to retain the details of construction herein shown, it is understood that

they may be modified to some extent, and that as regards the adjusting devices the essence of the invention consists in employing with a thermostat devices for effecting two independent adjustments.

Having thus described my invention, what I claim is—

1. In combination with the thermostat-bar and the pivoted arm or lever by which it is supported, the main adjusting-screw and the secondary adjusting-screw carried thereby. 40

2. In an electric thermostat, the combination of the vibratory thermostatic bar and its conducting-finger, the two contact-points on opposite sides of said finger, and stationary stops, substantially as described, to limit the movement of the bar and thus prevent the formation of a short circuit. 45

3. The combination of the thermostat, the main adjusting-screw, the intermediate adjusting-screw, and the index-plate. 50

In testimony whereof I hereunto set my hand, this 19th day of July, 1886, in the presence of two attesting witnesses.

WARREN S. JOHNSON.
